UNITED STATES PATENT OFFICE.

JOHN FISH, OF SUMMIT, NEW JERSEY, ASSIGNOR OF ONE-THIRD TO LORENZO BURHAUS, OF BROOKLYN, NEW YORK.

STEAM-GENERATOR.

SPECIFICATION forming part of Letters Patent No. 331,783, dated December 8, 1885.

Application filed April 3, 1885. Serial No. 161,167. (No model.)

To all whom it may concern:

Be it known that I, JOHN FISH, of Summit, in the county of Union and State of New Jersey, have invented a certain new and useful 5 Improvement in Steam-Generators, of which the following is a specification.

I will describe a steam-generator embodying my improvement, and then point out the various features of the improvement in the claims.

10 In the accompanying drawings, Figure 1 is a central vertical section of a steam-generator embodying my improvement. Fig. 2 is a central vertical section of certain parts thereof on a larger scale.

15 Similar letters of reference designate corresponding parts in both figures.

The shell A of the steam-generator, as here shown, is intended to be cylindrical. In the lower part is a fire-chamber, B, which may

20 be of any desirable construction, provided with grate-bars of any approved type, and with a door, B'. Below the fire-chamber is an ash-pit, C. Around the fire-chamber and between it and the shell of the generator is a 25 water-space or water-leg, a. Flues consisting of tubes D extend from the fire-chamber to a smoke-chamber, E. An outlet-flue, F, extends from this smoke-chamber. Above the smoke-chamber is a steam and water chamber, G.

30 These various parts may be of any desirable material and of any approved construction. It will be understood that the tubes D are submerged in water. The main shell A of the generator, however, ends at the top of the 35 smoke-chamber, and the steam-chamber is made a separate structure and fitted to the upper edge of the shell A, so as to form the top of the smoke-chamber.

H designates circulating pipe bolts, of which 40 there may be any suitable number. At the lower ends they may be secured by screw-

threads, or by expanding them into the bottom of the smoke-chamber E, so that they will communicate with the water-space below.

45 Some distance above the lower ends of these circulating-pipe bolts they are provided with outwardly-extending flanges b. Upon the top of these flanges gaskets of copper, c, are fitted, and the steam-chamber is fitted 50 to them above these gaskets. They extend through the steam-chamber, and have copper

gaskets d fitted to them above the steam-chamber. Nuts e, shaped to form caps, are fitted to screw-threads at their upper ends. These nuts in conjunction with the circulating-pipe 55 bolts, serve to secure the steam-chamber to the shell A and smoke-chamber E of the generator. The gaskets c d preserve tight joints where the circulating-pipe bolts pass through the steam-chamber. The circulating-pipe 60 bolts, as their name implies, are hollow. They have longitudinal openings f within the steam-chamber. Such openings consist of slots, and may be of any suitable number. They are shown as extending above the water-line of 65 the generator in the steam-chamber. The circulating-pipe bolts establish communication between the water-space of the generator, which is below the smoke-chamber and the steam-chamber.

I designate pipes, some of which extend down into the water-space a and rest upon the bottom thereof, and others of which or another of which derives support by resting upon the top of the fire-chamber. The lower 70 ends of these pipes I are notched or channeled off, so that water can enter them. At the upper ends these pipes are bell-mouthed and fit quite snugly within the circulating-pipe bolts H. The upper ends of the pipes I 75 are below the water-line in the steam-chamber. Water, as it becomes heated, rises in the circulating-pipe bolts H from the water-space below the smoke-chamber, and is discharged into the steam and water chamber. The bell- 80 mouths of the pipes I deflect the water outward. Cooler water in the steam and water chamber descends from the steam and water chamber through the circulating-pipes I into the water-space, which is below the smoke- 85 chamber. Thus a constant and valuable circulation is kept up.

What I claim as my invention, and desire to secure by Letters Patent, is—

1. In a steam-generator, the combination of 95 a main water-space, a steam and water chamber, an intermediate smoke-chamber, and pipe-bolts extending between the main water-space and the steam-chamber, and serving to establish communication between the same and 100 connect the parts together, substantially as specified.

2. In a steam-generator, the combination of a main water-space, a steam and water chamber, an intermediate smoke-chamber, the circulating-pipe bolts H, and the pipes I, substantially as specified.

3. In a steam-generator, the combination of a main water-space, a steam and water chamber, an intermediate smoke-chamber, the circulating-pipe bolts H, and the pipes I, having 10 bell-mouths, substantially as specified.

4. In a steam-generator, the combination of a main water-space, a steam and water chamber, an intermediate smoke-chamber, the circulating-pipe bolts H, the flanges b, the gaskets c d, and the cap-nuts e, substantially as 15 specified.

JOHN FISH.
